BRUSH SUPPORT

James Miles, Los Angeles, Calif.

Application February 18, 1947, Serial No. 729,283

5 Claims. (Cl. 248—110)

1

This invention relates to a device to be used by a painter when conducting painting operations, or when applying any liquid to a surface by means of a brush. Many such operations are performed while the painter is standing on a ladder, and from time to time it is necessary for him to put down the brush. In doing this, it is desirable to rest the brush in some way so that it can drip into the pail or can containing the liquid or paint that is being used.

Some devices have been produced for enabling the brush to be supported over the contents of the can, but many of these have the character of a clamp for grasping the brush handle, and in some of these devices where a rest is provided on which the handle of the brush rests, the construction is not such as to prevent the brush from turning over and falling into the pail or bucket.

One of the objects of this invention is to provide a device of this character, which can be readily operated with one hand to set it in a position to receive and support the brush in a substantially upright position above the contents of the pail; and which is so constructed that normally the support for the brush is maintained in a retracted or folded condition adjacent the side of the pail.

Another object of the invention is to provide a supporting member operating as a rest on which the brush can be placed, having features of construction which will enable it to prevent the brush from falling over after it is set in place.

Another object of the invention is to provide a device of this character, having a supporting member in the nature of an arm capable of swinging from a retracted position, into an extended position in which it is adapted to engage the bristles of the brush just below the shoulder of the handle when the brush is slipped down into place, and to provide means including resilient means, or a spring, cooperating with the parts of the device in such a way that the supporting arm for the brush can maintain itself in its extended position after being set in such position, but which, after having supported the brush, will effect the return of the support to a retracted position when the brush is removed, thereby leaving the interior of the pail substantially free and unobstructed.

Further objects of the invention will appear hereinafter.

The invention consists in the novel parts and combinations of parts to be described hereinafter,

2

all of which contribute to produce an efficient brush support.

A preferred embodiment of the invention is described in the following specification, while the broad scope of the invention is pointed out in the appended claims.

In the drawings:

Fig. 1 is a vertical section taken through the side wall of a paint-bucket or pail, and illustrating a device embodying my invention, applied to the same. In this view, my device is shown partially in elevation, and partially in section; and a paint brush is illustrated in dotted lines, supported by the device.

Fig. 2 is an elevation looking upon the device from the interior of the pail, and showing a portion of the bracket broken away and partially in section; a portion of the supporting member or hook-member, is also shown in vertical section. This view also shows a supporting-member in its extended position, that is to say, with the movable parts of the device set to receive the brush.

Fig. 3 is a plan showing a portion of the wall of the pail, and illustrating my device applied to the same, and with the hook-member in its retracted or folded position.

Referring more particularly to the parts, 1 indicates a portion of the wall of the cylindrical bucket or pail such as used by painters for holding paint, from which they are applying paint on a wall or other surface, by means of a brush 2, such as illustrated in dotted lines. This bucket or pail is usually provided with a bail 3 (not illustrated) for supporting and carrying it. These pails or buckets usually have a body of cylindrical form, formed of sheet metal.

In applying my invention in the construction of a device to be applied to a bucket such as illustrated, I provide a frame-member, or bracket 3, that has an inner member or body 4 of plate-like form, that is formed with a socket 5 at its upper end, enabling it to be shoved down over the upper edge or lip 6 of the bucket; and in order to hold the bracket in place, it is provided on its outer side with an extension 7, which extends downwardly, and the lower end of which is formed into, or provided with, an upwardly extending inclined tongue 8. This tongue presses yieldingly and resiliently against the outer wall of the pail, and holds the bracket in position. If desired, the body 4 of the bracket may taper slightly toward its lower end, and at this point I attach a supporting member, or hook-member 9. This hook-member is preferably composed of a relatively

long extension or arm 10 toward its outer end, and has a relatively short arm 11 that is attached on a pivot bolt or pin 12 to the lower end of the body 4. This may be accomplished by attaching the end of the short arm 11 between two lugs 13 that project outwardly from the adjacent face of the body 4.

In accordance with my invention, in addition to providing this pivoted supporting arm, I also provide means for returning it to a folded or retracted position in which the tip of the long arm 10 will lie substantially against the upper portion of the bracket, and this means preferably is constructed so that a manually-operated part connected with the hook-member, can be operated by one hand, or finger, to place the arm or hook 9 in the set position, such as that illustrated in Fig. 1, that adapts it to receive the brush and support the same in substantially the position in which it is illustrated in dotted lines in Fig. 1. In order to accomplish this, I prefer to provide an operating stem 14, the lower portion 15 of which is illustrated as of smaller diameter than the upper portion 16. This lower portion or extension 15 is bent laterally to form a hook 17 that is received in a pivot opening or eye 18 formed in the inner end of the short arm 11. The upper end portion 16 of the stem 14, is guided on the upper end or saddle portion 19 of the bracket that rests upon the lip of the pail, and in the present instance, it is guided to slide through a guide opening 20 in the saddle portion 19, through which the part 16 of the stem slides freely and loosely. Near its upper end, and on one of its lateral sides, a notch or shoulder 21 is provided. With this construction, by reason of the presence of this shoulder, if the upper end of the stem 15 is pressed downwardly and laterally by a force applied in a direction indicated by the arrow 22 in Fig. 2, the notch or shoulder 21 can be projected under the lower edge of the opening 20, and when released, will maintain the stem 15 in this depressed position with the hook-member 9 in its corresponding extended position illustrated in Fig. 1. In order to retract the hook-member 9 and move it up to its folded position illustrated in Fig. 3, when the paint brush 2 is lifted from it, I provide resilient means preferably in the form of a coil spring 23, the upper end of which is anchored in an opening 24 disposed laterally, and at an elevated position on the body 4 of the bracket. The lower end of the spring 23 is formed into a ring-shaped integral hook 25 that extends around the lower portion 15 of the stem, and seats against the shoulder 26 that is formed at the junction of the two portions 15 and 16 of the stem. This spring 23 is a light spring, and exerts insufficient force to dislodge the shoulder 21 from engagement with the edge of the opening 20, but as soon as the brush 2 is rested on the hook-member 9, the weight of the brush will depress the hook-member 9 slightly to an extent permitted by a stop-toe 27 that will engage the adjacent face of the body 4 of the bracket. In other words, the stem 15 will move down far enough to dislodge the shoulder 21 from the edge of the opening 20, whereupon the spring 23 will pull up on the stem 15, and swing the hook-member 9 up to its retracted and elevated position, where it will be out of the way for the painter.

I prefer to make the hook-member 9 out of plate material, so that it presents side faces 28 which are in a substantially vertical plane. These side faces present sufficient area to insure that the brush will be maintained in an upright posi-

tion. In other words, the weight of the handle of the brush can not operate to permit the brush to rotate on the hook-member in the medial plane of the brush, so that it would fall away from the position in which it is supported. And, furthermore, in order to insure that the brush handle will not tip toward the interior or axis of the pail, nor outwardly toward the wall of the pail, I prefer to have the arms 10 and 11 of the hook 9 disposed at an angle to each other, so that an angular socket 29 is formed, at which the brush will be supported with the shoulders 30 of the brush handle substantially resting upon the upper edges of these arms.

15 It will be evident that in using this device, the painter can readily push the stem 14 downwardly, so as to move the hook-member 9 to its extended position, whereupon he can rest the brush on the same, in the position which is illustrated in dotted lines in Fig. 1. As soon as the brush is lifted off of the hook-member, of course the spring 23 will immediately return the hook-member to its folded position adjacent the side of the pail.

20 25 In practice, if desired, the spring 23, and the operating stem 14, may be enclosed in a casing, which casing would be provided with a slot through which the hook 9 would project. The use of this casing, however, is unimportant, and it 30 has been omitted to facilitate the disclosure of the invention.

Many other embodiments of the invention may be resorted to without departing from the spirit of the invention.

35 I claim as my invention:

1. In a device for supporting a brush upon a painter's pail or the like, the combination of a frame-member having means for supporting the same adjacent the lip of the pail, a hook-member movably attached to the frame-member, manually-operated means for moving the hook-member into an extended position, projecting inwardly from the side of the pail, and for maintaining the same extended to receive and support the brush in a position to drip into the pail; and automatic means for moving the hook-member to a retracted position brought into action by the removal of the brush from the hook-member.

2. A hook for supporting a paint brush upon a painter's pail or the like, according to claim 1, in which the hook-member is pivotally attached to the frame-member so as to swing downwardly and inwardly toward the interior of the pail; in which the frame-member has means for guiding the frame-member; and resilient means associated therewith for normally maintaining the hook-member in a retracted position.

3. In a hook for supporting a paint brush upon a painter's pail or the like, the combination of a frame-member including a bracket having means for attaching the same to the lip of the pail, a hook-member pivotally attached to the bracket, a stem guided to slide on the bracket and operatively connected to the hook-member for swinging the same downwardly on its pivot to project it inwardly toward the interior of the pail, a spring associated with said stem for urging the same upwardly and laterally; said stem having a shoulder on the side remote from said spring adapted to engage the bracket when the stem is forced downwardly and laterally away from the location of the spring, said shoulder operating to resist the force exerted by the spring and maintain the hook in an extended position; said parts cooperating 70 75 when the brush is hung on the hook to depress

the stem further and release the shoulder from the bracket, so that when the brush is removed from the hook, the spring retracts the hook toward the side of the pail.

4. In a hook for supporting a paint brush upon a painter's pail or the like, the combination of a frame-member including a bracket having means for attaching the same to the lip of the pail, a hook-member pivotally attached to the bracket, manually-operated means mounted on the bracket and operatively connected with the hook-member for swinging the same downwardly on its pivot to project it inwardly toward the interior of the pail, means for urging the hook-member upwardly; said parts cooperating when the brush is hung on the hook-member to maintain the spring extended; said spring operating when the brush is removed from the hook-member, to retract the hook-member into its position of rest adjacent to the side of the pail.

5. In a device for supporting a painter's brush

5 10

upon a painter's pail or the like, the combination of a bracket having means for securing the same to the pail, and a supporting member to be engaged by the brush, pivotally attached to the bracket, capable of swinging inwardly into an extended position adapted to support the brush over the contents of the pail, and a spring for retracting the said supporting member when the brush is removed from the same.

JAMES MILES.
